UNITED STATES PATENT OFFICE.

HORACE C. WILCOX, OF WEST MERIDEN, CONNECTICUT, ASSIGNOR TO THE MERIDEN BRITANNIA COMPANY, OF SAME PLACE.

DESIGN FOR HANDLES OF TABLE-CASTERS.

Specification forming part of Design No. 7,067, dated December 16, 1873; application filed November 22, 1873.
[Term of Patent 7 years.]

To all whom it may concern:

Be it known that I, HORACE C. WILCOX, of West Meriden, in the county of New Haven and State of Connecticut, have invented a new Design for Handles of Table-Casters; and I do hereby declare the following, when taken in connection with the accompanying drawings and the letters of reference marked thereon, to be a full, clear, and exact description of the same, and which said drawings constitute part of this specification, and represent, in—

Figure 1 a front view, and in Fig. 2 a side view.

This invention relates to a design for handles of table-casters and like articles; and it consists in the peculiar configuration of the handle above the socket, as shown in the accompanying illustration, and as more fully hereinafter described.

A is the socket, by which the handle is at-

tached to the easter-frame, and may be of any desirable form. The handle B is of loop form, the two ends *aa* of the loop attached to the socket upon opposite sides, as seen in Fig. 1. Above the socket each arm is divided, and the parts C C drawn together in the center to form a complete loop above the socket, as shown in Fig. 1.

This handle may be ornamented by chasing or otherwise, but the ornamentation constitutes no part of the design.

I claim as my invention—

The design for handle for table-casters, in which the sides of the loop are divided and the inner divisions drawn together above the socket, as herein described, and shown in the accompanying illustration.

Witnesses: HORACE C. WILCOX.

C. P. IVES,
JAMES P. PLATT.
